APPARATUS FOR THE WET-TREATMENT
OF TEXTILE GOODS

Otto Gretler, Zurich, Switzerland

Application June 21, 1935, Serial No. 27,663
In Germany May 4, 1934

5 Claims. (Cl. 8—19)

The present invention relates to improvements in the wet-treatment of textile goods.

The invention comprehends inter alia an apparatus for the wet-treatment of textile-goods with conveyers lowering and lifting the textile-goods in a treating liquid in such a manner, as to obtain a speed of the downward motion of the conveyers greater than the speed of the downward motion of the textile-goods in the liquid.

10 A further object of my invention is to couple the vertical descent of the conveyers with a lateral motion.

The apparatus comprises conveyers pivoted to endless chains by means of arms, and resting upon guide-plates having the form of a saw-blade, so that the operation of the conveyers is determined by the form of the guide-plates.

15 The invention will be fully understood from the following description read in connection with the accompanying drawing in which:

20 Figs. 1-3 show the apparatus diagrammatically, Fig. 4 shows a diagram of the position of the textile goods before and after the descent and lateral motion of a conveyor

25 Fig. 5 shows an alternative form of a conveyor. Referring to the drawing, the invention includes tank I in which conveyors 4, 4', carrying the textile-goods 5, are pivoted by means of arms 3, 3' to endless chains 2, 2' (2' not shown). The conveyors 4, 4' rest upon guide-plates 6, 6' (6' not shown) situated parallel the walls of tank I. The upper edges of the said guide-plates are provided with teeth in saw-blade fashion. Each tooth is designed in such a manner that the side 30 facing the direction of movement is set at a bevel angle to the horizontally disposed base line extending between any two adjacent teeth while the other side of said tooth, facing in the opposite direction is set at a right angle to the said base line. When the chains are set in motion, the conveyors 4, 4' arriving at the highest points of the teeth drop down to the base line, the descent being so rapid that the more slowly descending textile-goods will, for some time, remain suspended in the liquid without being supported by the conveyors. Due to the progressing motion of the chain, the descending conveyor will be subject not only to the rapid downward motion along the rectangular side of the tooth but, at the same time, to the lateral motion parallel to the horizontal base line. The resultant of both these motions will bring the conveyor in contact with the base line at a point removed from the vertex of the right angle formed by the base line and the 35 vertical side of the last tooth in a direction oppo-

site the direction of movement. The continued motion of the chain will then cause the conveyor, after having hit the base line, to perform a purely lateral motion along the edge of the same until the beveled side of the next tooth is reached. 5 The conveyor will thereupon ascend the beveled side of the next tooth picking up on its way the slowly descending textile-goods, supporting the same, however, now at a different point than before, and upon reaching the top of the tooth 10 the cycle is repeated.

By this arrangement the places of support of the textile-goods by the conveyors (Fig. 4) while being immersed are constantly changed.

The dotted line (Fig. 4) indicates the approximate position of the textile-goods after the conveyors have reached their end position viz. the point at which they again commence to ascend.

In most cases conveyors of circular cross-section, as shown in Figs. 1-4 are sufficient conveyors 20 of different shape or form such as, for instance, the one shown in Fig. 5, may be used with advantage, particularly for finer materials.

The speed of operation of the conveyors may be changed to suit prevailing conditions and 25 requirements.

What I claim is:—

1. Apparatus for the wet treatment of textile-goods comprising a tank, a plurality of bars adapted to ascend and descend in said tank, each 30 of said bars being adapted while ascending to lift textile-goods in said tank, and while descending to release textile-goods, the speed of descent of each of said bars being greater than the speed of descent of textile goods in liquid, 35 each of said bars being adapted to contact and lift textile-goods upon each successive ascension at a point in advance of the previous point of contact, a guide-plate provided with teeth in saw-blade fashion, each of said teeth being set 40 at a bevel angle on one side, and at a right angle on the other, any two adjacent teeth being spaced apart on a horizontal base line so as to impart to each of said bars a downward motion more rapid than the upward motion, and a forward 45 motion immediately following the said downward motion and immediately preceding the said upward motion, an endless chain adapted to move said plurality of bars progressively forward in said tank, and adapted to impart to each of 50 said bars, while descending, a simultaneous forward motion.

2. Apparatus for the wet treatment of textile goods, comprising a tank, a plurality of means in said tank adapted to carry textile goods, and 55

to ascend and descend in said tank, the speed of descension being greater than the rate of fall of textile goods in liquid, and driving means adapted to move said plurality of means progressively forward in said tank, each of said plurality of means being adapted to contact and lift textile goods upon each successive ascension at a point in advance of the previous point of contact.

3. Apparatus for the wet treatment of textile goods comprising a tank, a plurality of means in said tank adapted to carry textile goods, and to ascend and descend in said tank, the speed of ascension being slower than the speed of descension, and the speed of descension being greater than the rate of fall of textile goods in liquid, and driving means adapted to move said plurality of means progressively forward in said tank, each of said plurality of means being adapted to contact and lift textile goods upon each successive ascension at a point in advance of the previous point of contact.

4. Apparatus for the wet treatment of textile

goods comprising a tank, a plurality of bars arranged in parallel and spaced apart from one another, driving means adapted to move said bars progressively forward in said tank, and guide plates coating with said bars adapted to cause said bars to ascend and descend in said tank, the speed of descension being greater than the rate of fall of textile goods in liquid, each of said bars being adapted to contact and lift textile goods upon each successive ascension at a point 10 in advance of the previous point of contact.

5. Apparatus for the wet treatment of textile goods comprising a tank, a plurality of bars arranged in parallel and spaced apart from one another, driving means adapted to move said bars progressively forward in said tank, said bars being movably connected to said driving means, and a serrated guide plate coating with said bars and adapted to cause said bars to ascend and descend in said tank as they are moved 15 progressively forward by said driving means.

to ascend and descend in said tank, the speed of descension being greater than the rate of fall of textile goods in liquid, and driving means adapted to move said plurality of means progressively forward in said tank, each of said plurality of means being adapted to contact and lift textile goods upon each successive ascension at a point in advance of the previous point of contact.

3. Apparatus for the wet treatment of textile goods comprising a tank, a plurality of means in said tank adapted to carry textile goods, and to ascend and descend in said tank, the speed of ascension being slower than the speed of descension, and the speed of descension being greater than the rate of fall of textile goods in liquid, and driving means adapted to move said plurality of means progressively forward in said tank, each of said plurality of means being adapted to contact and lift textile goods upon each successive ascension at a point in advance of the previous point of contact.

4. Apparatus for the wet treatment of textile

goods comprising a tank, a plurality of bars arranged in parallel and spaced apart from one another, driving means adapted to move said bars progressively forward in said tank, and guide plates coating with said bars adapted to cause said bars to ascend and descend in said tank, the speed of descension being greater than the rate of fall of textile goods in liquid, each of said bars being adapted to contact and lift textile goods upon each successive ascension at a point 10 in advance of the previous point of contact.

5. Apparatus for the wet treatment of textile goods comprising a tank, a plurality of bars arranged in parallel and spaced apart from one another, driving means adapted to move said bars progressively forward in said tank, said bars being movably connected to said driving means, and a serrated guide plate coating with said bars and adapted to cause said bars to ascend and descend in said tank as they are moved 15 progressively forward by said driving means.
